INSTRUMENT FOR ELECTROSURGICAL
RESECTIONAbram I. Willinsky, Toronto, Ontario, Canada,
assignor to American Cystoscope Makers, Inc.,
New York, N. Y., a corporation of New York

Application September 26, 1945, Serial No. 618,683

13 Claims. (Cl. 128—303.14)

1

This invention relates to a surgical instrument, and in one of its more specific aspects to such an instrument capable of readily removing protrusions, tissue growths, and the like, by resection with the aid of a high frequency electric current.

The instrument of this invention is particularly well suited for use in resecting tumorous growths or other masses of body tissue in body passages and cavities. For example, the present invention may be readily employed for the resection of protrusions in the urethra and bladder neck, and for the excision of undesirable growths on the prostate gland and other internal organs.

As will be apparent to persons skilled in the art from the detailed description that follows, the instrument may be inserted in a body passage or cavity to the region of the protrusion or the like which is to be removed, whereupon the protrusion or the like may be resected by a high frequency cutting electrode means under conditions of illuminated vision. One of the features of the invention resides in arranging the endoscopic sheath, the telescope, and the cutting electrode means in such a manner that they may be rotated as a unit with respect to a supporting structure which preferably includes a pistol type grip. This permits of ready angular adjustment of the unit with respect to the supporting means, thereby eliminating awkwardness and strain on the part of the surgeon in operating the instrument.

The benefits derived by employing the instrument of this invention will be readily apparent when it is realized that in present-day resectoscopes, the endoscopic tube, telescope, and cutting electrode means are all mounted in fixed non-rotatable relation with respect to their supporting structure. When the surgeon desires to remove tissue growth from sections to the right or to the left of the original cut or from sections above the initial cut, it is necessary that he impart a rotary movement to the entire conventional instrument with his hand. This results in strain and awkward movement on the part of the surgeon, as his arm and hand employed in operating the instrument must necessarily be twisted into trying and unnatural positions. For example, when it is essential that the cutting operation take place in a position corresponding to "three o'clock" or "nine o'clock," the instrument as a whole must be turned, gripped and manipulated correspondingly, thereby making it difficult for the surgeon to carry out the resecting procedure.

My resecting instrument obviates the difficulties referred to above, as it permits the supporting means to be held in a desired predeter-

2

mined position while the endoscopic sheath, telescope and/or cutting electrode means may be independently rotated with respect to the supporting means to the desired cutting position.

5 To this end the instrument comprises an endoscopic sheath provided with a lateral fenestra at its forward end and having an illuminated telescope and cutting electrode means removably disposed therein. These elements may be considered as constituting a first unit. A second unit includes a support, preferably in the nature of a pistol grip, and a plurality of spaced bearing members carried by the pistol grip. At least one of the bearing members is rigidly secured to the pistol grip, while another thereof is slidable along the pistol grip. Secured to the first unit and rotatably engaging the bearing members of the second unit is a means whereby rotation may be imparted to the first unit with respect to the 10 second unit. By this construction the first unit may be adjusted to desired angular position with respect to the second unit, thereby facilitating manipulation of the instrument as a whole under operating conditions. The instrument includes 15 appropriate means for supplying illumination to the telescope and devices for transmitting a high frequency electric current to the cutting electrode means.

The cutting electrode means is so arranged 20 that it may be moved longitudinally with respect to the endoscopic tube and the pistol grip through the medium of suitable means coaxing therewith and with the slidable bearing. As will be apparent from the detailed description further along 25 and from the annexed drawings, the cutting electrode means is movable longitudinally with respect to the endoscopic tube independently of the rotation of the first unit with respect to the second unit.

It is an important object of this invention to 30 provide an improved surgical instrument for readily resecting a protrusion or the like with the aid of a high frequency electric current.

This invention has for another object the provision 35 of an instrument of the character described having certain elements adjustable angularly with respect to a supporting means whereby manipulation and operation of the instrument are greatly facilitated.

40 It is another object of the invention to provide 45 an electrosurgical instrument wherein an endoscopic sheath, a telescope and/or a cutting electrode means are rotatable as a unit with respect to a supporting structure, and wherein the cutting electrode means is independently movable

longitudinally with respect to the endoscopic tube.

A further object of the invention is the provision of an electrosurgical instrument of the character indicated that is relatively simple and compact in design, reasonable in initial and upkeep costs, and capable of performing its intended functions in an effective and trouble-free manner.

These objects, as well as other objects, together with the advantages obtainable by the practice of this invention, will be readily understood by persons skilled in the art upon reference to the following detailed description, taken in conjunction with the attached drawings, which respectively describe and illustrate a preferred embodiment of the invention.

In the drawings:

Figure 1 is a side elevational view of an instrument embodying the devices of the invention in one relative position, partly in central vertical cross section and with parts broken away for better illustration;

Figure 2 is a cross-sectional view taken along line 2—2 of Figure 1;

Figure 3 is a side elevational view of the instrument with the devices in another relative position;

Figure 4 is an enlarged cross-sectional view taken along line 4—4 of Figure 1;

Figure 5 is an enlarged cross-sectional view taken along line 5—5 of Figure 1;

Figure 6 is an enlarged cross-sectional view taken along staggered line 6—6 of Figure 1;

Figure 7 is an enlarged cross-sectional view taken along line 7—7 of Figure 1;

Figure 8 is an enlarged cross-sectional view taken along staggered line 8—8 of Figure 1; and

Figure 9 is an enlarged cross-sectional view taken along staggered line 9—9 of Figure 3.

Referring now to the drawings wherein like reference characters denote corresponding parts throughout the several views, and more particularly to Figures 1 and 2, there is shown an endoscopic tube 10 provided at its forward end with a lateral fenestra 11 and provided with external threads at its rearward end for engagement with corresponding internal threads in a flared collar 12. An inlet conduit 13, secured to collar 12, is adapted to introduce an irrigating liquid into the interior of endoscopic tube 10, the irrigating fluid being withdrawn from the endoscopic tube through a discharge conduit 14, which is equipped with a control valve 15 having an operating lever 16. Collar 12 is formed with a forwardly and inwardly tapered recess 17 that engages a connector device 18, having a frusto-conical forward portion, in a fluid-tight manner. As is best shown in Figure 5, device 18 is provided with a pair of separate parallel openings 19 and 20 for the reception of a telescope 21 and a cutting electrode means 22, respectively, that will be described in greater detail further along herein. Both the telescope and the cutting electrode means form adequate seals with the corresponding openings in device 18, and the cutting electrode means is additionally capable of being readily moved longitudinally through its opening 20.

Affixed to device 18 in any desired manner is a longitudinally bifurcated arm 23 (Figure 3), adapted to receive a post 24 that projects upwardly of collar 12. Post 24 carries a locking attachment 25 for effecting coupling engagement between the post and arm 23. Device 18 is tapped, as indicated in Figure 2, to threadedly engage the rearward end portion of a member 26 that is preferably coaxial with endoscopic tube 10, and

that is formed with a pair of elongated parallel longitudinal arcuate grooves 27 and 28 (Figure 4), which respectively accommodate forward portions of telescope 21 and cutting electrode means 22.

Endoscopic tube 10, telescope 21, and cutting electrode means 22 are adapted to be mounted on and rotated as a unit with respect to a second unit comprising a support, generally denoted by numeral 30, that will now be described. Support 30 includes a handle 31, preferably of the pistol grip type and composed of a suitable electrical insulating material. As is shown in Figure 1, pistol grip 31 is notched or recessed at 32. Secured to pistol grip 31 by rivets 33 is a pair of spaced parallel plates 34, each having an integral extension 35. A bracket 38, having a pair of spaced laterally projecting arms 39 (Figures 3 and 5), is arranged across the free ends of extensions 35 and is secured thereto by screws 40. An externally threaded hollow plug 41 extends through bracket 38 and serves as the bearing for the forward end of a rod 42, which has its rearward end journaled in a blind bore formed in a second threaded plug 43 that is carried by pistol grip 31 (Figure 1).

This invention includes a mechanism 45, that is reciprocable along rod 42 and extensions 35 and that is best shown in Figures 1, 2, 3 and 7. Mechanism 45 includes a main body portion 46 that is flanged at the top to ride along the upper surfaces of extensions 35 and that is bored at 47 to freely receive rod 42. Depending from body portion 46 is an actuating trigger or curved finger lever 48. Integral with body portion 46 and extending rearwardly therefrom, is a yoke 49 that carries a roller 50, rotatable about a pin 51 and along the under surface of each extension 35. Coaxial with rod 42 is a compression spring 52 that bears at its opposite ends against body portion 46 and plug 43 to normally and yieldingly maintain mechanism 45 in protracted position, as is indicated in full lines in Figures 1 and 3. Mechanism 45 may be retracted against the action of compression spring 52 to the position indicated by the dot-and-dash lines in Figure 1 by merely engaging trigger 48 and exerting a force toward the right thereon.

Integral with bracket 38 is an upstanding first bearing member or ring 55. The rearward end portion of device 18 is of reduced diameter and is rotatably accommodated in bearing member 55. A backing plate 56, having a central opening 57 through which telescope 21 and cutting electrode means 22 are adapted to pass, is affixed to the rear end face of device 18 by means of screws 58. Backing plate 56 prevents accidental disengagement of device 18 from bearing member 55.

Extending upwardly from mechanism 45 is a second bearing member 60 in the nature of a saddle in which a flanged disc 61 is rotatably mounted. A plate 62 is positioned immediately adjacent the forward end face of disc 61 and has a split clamping plate 63 secured thereto by screws 64 (Figure 6). Clamping plate 64 carries a knurled clamping screw 65. Immediately adjacent the rearward end face of disc 61 is a hollow block 66, composed of a suitable insulating material, such as hard rubber, and having an electrically conductive ring 67 and an integral electrical terminal nipple 68 imbedded therein. A plate 69 is attached to the rear end face of block 66 by means of screws 70. A screw 71 in turn joins plate 62, disc 61 and block 66 into a unitary assembly, which is rotatable in bearing member 60 and which is reciprocable with respect to the endoscopic tube 10 and support 30 in response

to actuation of mechanism 45. It should be borne in mind that clamping plate 63, plate 62, disc 61, block 66 and plate 69 are readily reciprocable as a unit with respect to telescope 21. On the other hand, cutting electrode means 22 is clamped to plate 63 through the action of clamping screw 65 and is hence reciprocable with respect to endoscopic tube 10 upon actuation of mechanism 45.

Attached to plates 34 by screws 72 is a combined bracket and cover plate 73, which carries a third bearing member or ring 74. It may be well to point out at this time that bearing members 55, 60 and 74 are coaxial under various operating conditions. A flanged disc 75 is rotatably mounted in bearing member 74 and has a backing plate 76 affixed thereto by a series of screws 77 to prevent accidental disengagement. A split clamping plate 78, similar to earlier referred to clamping plate 63, is attached to the rear end face of disc 75 by means of screws 79 and has a knurled clamping screw 80, whereby telescope 21 may be readily and non-rotatably secured to clamping plate 78 and, therefore, to disc 75. A pair of parallel guide rails 81 extend through various elements as shown in Figure 2, and are secured at their opposite ends to backing plates 56 and 76, respectively. By virtue of the construction illustrated and described, endoscopic tube 10, telescope 21 and cutting electrode means 22 may be rotated as a unit about the coincident axes of bearing members 55, 60 and 74. Also, as set forth above, cutting electrode means 22 is separately reciprocable by simply actuating mechanism 45.

Telescope 21 includes a main tubular body 82 of relatively small diameter adapted to be inserted through the respective assemblies rotatably mounted in third bearing member 74, second bearing member 60, and first bearing member 55 in the order named, and thence through opening 19 in connector device 18 and in registration with arcuate groove 27 in member 26 until it assumes the position shown in Figure 1. An electric lamp 83 is attached to the forward end of tubular body 82 to provide illumination through fenestra 11 when the instrument is assembled. At the rearward end of tubular body 82 is an eye piece 84. The telescope lens system (not shown) may be of any suitable type, such as, for example, the lens system disclosed in the patent to R. H. Wappler 1,680,490 granted August 14, 1928. The telescope is provided with the usual electrical terminal device 85 for connection to a convenient source of electricity (not shown) for energizing lamp 83. A bifurcated arm 86, affixed to clamping plate 78 by a screw 87, engages electrical terminal device 85, as is shown in Figures 1 and 3. As was indicated above, telescope 21 is locked to the assembly rotatably mounted in third bearing member 74 through the coaction of clamping plate 78 and clamping screw 80.

Referring next to cutting electrode means 22, the same includes an electrically conductive rod 90 concentrically disposed within and insulated from a tubular shaft-like element 91, having its rearward portion clamped in the assembly rotatably mounted in second bearing member 60. Tubular element 91 is movable longitudinally through connector device 18 and reposes in arcuate groove 28. The rearward end portion of rod 90 extends beyond tubular element 91 and is in electrical contact with conductive ring 67. The forward end portion of rod 90 also extends beyond tubular element 91 and is split to obtain a

pair of divergent arched arms 93 that carry a high frequency U-shaped cutting element 94.

The mode of operation of the instrument for the resection of a mass of tissue in a body cavity will now be briefly described. Locking attachment 25 is disengaged from bifurcated arm 23 and the devices within endoscopic tube 10 are removed therefrom. A suitable obturator (not shown) is then placed in the endoscopic tube and the tube is inserted in the body cavity in the usual manner until fenestra 11 arrives at the approximate location of the tissue growth. Body fluids are withdrawn through endoscopic tube 10 and discharge conduit 14, as allowed by valve 15, and the obturator is removed. The various devices are then assembled in the relative positions shown in Figure 1, electrical connection with lamp 83 being made through terminal device 85. Nipple 68 is then connected with one terminal of an appropriate source of high frequency electric current, the patient being grounded or suitably connected with the other terminal of the high frequency current source. An irrigating liquid may be introduced into the body cavity through inlet conduit 13 and the interior of endoscopic tube 10. The irrigating liquid is withdrawn by way of endoscopic tube 10 and discharge conduit 14. The surgeon is now ready to remove the tissue growth. He grasps pistol grip 31 in one hand, placing the index finger of that hand on trigger 48, and sights through telescope eye piece 84 to locate the exact region where it is desired to carry out the cutting operation. The tissue growth that is to be cut is accommodated within fenestra 11 and the high frequency electric circuit is completed. The surgeon exerts a pull on trigger 48 with his index finger, thereby moving body portion 46, bearing member 60, the assembly rotatably supported in bearing member 60, and cutting electrode means 22 toward the right, as viewed in Figure 1, and to the position indicated by the dot-and-dash lines, whereby a portion of the tissue growth is resected by cutting element 94. Upon release of trigger 48, mechanism 45 and the devices operated thereby are protracted to the full line position (Figure 1) due to the action of compression spring 52. If it is desired to remove tissue to the right or left of the original cut, the surgeon merely imparts sufficient relative rotational movement to the endoscopic tube, the telescope, and the cutting electrode means as a unit with respect to pistol grip 31, for example, by manipulating knurled disc 75 with the fingers of one hand while firmly grasping the pistol grip with his other hand, and then actuates trigger 48, as will be obvious from an inspection of the drawings.

From the foregoing, it is believed that the construction, operation and advantages of my present invention will be readily comprehended by persons skilled in the art. It is to be clearly understood, however, that various changes in the apparatus may be resorted to without departing from the spirit of the invention, as defined by the appended claims.

I claim:

1. In an instrument of the character described, a support, bearing means carried by the support, an endoscopic tube, a telescope in the tube and cutting electrode means in the tube, said tube, telescope and electrode means being united and rotatably mounted in the bearing means for simultaneous rotation with respect to the support, and means for effecting reciprocable move-

ment of the electrode means with respect to the tube and the support.

2. In an instrument of the character described, a support, bearing means carried by the support, an endoscopic tube, a telescope in the tube and cutting electrode means in the tube, said tube, telescope and electrode means being united and rotatably mounted in the bearing means for simultaneous rotation with respect to the support, means for normally and yieldingly maintaining the electrode means in a predetermined position with respect to the tube, and means for effecting reciprocable movement of the electrode means with respect to the tube and the support.

3. In an instrument of the character described, a first unit comprising an endoscopic tube, a telescope in the tube, and cutting electrode means in the tube, a second unit comprising a support and a plurality of spaced bearing members carried by the support, at least one of said bearing members being rigidly attached to the support and another of said bearing members being slideable along said support, means secured to the first unit and rotatably engaging the bearing members for imparting rotational movement to the first unit with respect to the second unit, and means connected to the slideable bearing member for imparting reciprocable movement to the electrode means with respect to the tube.

4. In an instrument of the character described, a first unit comprising an endoscopic tube, a telescope in the tube, and cutting electrode means in the tube, a second unit comprising a support and a plurality of spaced bearing members carried by the support, at least one of said bearing members being rigidly attached to the support and another of said bearing members being slideable along said support, means secured to the first unit and rotatably engaging the bearing members for imparting rotational movement to the first unit with respect to the second unit, means connected to the slideable bearing member for imparting reciprocable movement to the electrode means with respect to the tube, and means yieldingly urging said last mentioned means in one direction to normally maintain the cutting electrode in a predetermined position with respect to the tube.

5. In an instrument of the character described, a first unit comprising an endoscopic tube having a fenestra formed therein, a telescope fixedly positioned in the tube, and cutting electrode means longitudinally movable in the tube and having at least a portion thereof disposed in the region of the fenestra, a second unit comprising a support and a plurality of bearing members carried by the support, one of said bearing members being rigidly attached to the support, another of said bearing members being slideably mounted on the support, means fixedly secured to the first unit rearwardly of the fenestra and rotatably engaging the bearing members for imparting rotational movement to the first unit with respect to the second unit, means connected to the electrode means and to the slideable bearing member for normally and yieldingly maintaining the electrode means in a predetermined position with respect to the tube, and means connected to the slideable bearing means and the cutting electrode for imparting longitudinal movement to the latter with respect to the tube against the action of the last mentioned means.

6. A surgical instrument comprising a handle, a device for carrying instrumentalities rotatably and reciprocably mounted upon the handle, an

endoscopic tube for insertion into a body cavity removably and rotatably mounted upon the handle, a cutting electrode removably mounted upon the device and reciprocable within the tube, a telescope removably mounted upon the device and slideable thereon, means upon the handle to rotate the endoscopic tube and the device, and means upon the handle to reciprocate the device and the cutting electrode.

7. A surgical instrument comprising a handle, a disc rotatably mounted thereon, a device for carrying instrumentalities rotatable with respect to the handle and reciprocable with respect to the handle and the disc, means connecting the disc and the device to impart rotating motion of the former to the latter, a cutting electrode mounted upon the device and movable therewith, a telescope slideably mounted on the device and rotatable therewith, means upon the handle to reciprocate the device and the cutting electrode, and an endoscopic tube surrounding the cutting electrode and the telescope for insertion into a body cavity, said endoscopic tube being removably mounted upon the handle and rotatable with the disc.

8. A surgical instrument comprising a handle, a device for carrying instrumentalities rotatably mounted upon the handle, an endoscopic tube mounted upon the handle and rotatable with the device, cutting electrode means within the endoscopic tube and rotatable with the device, and means for imparting rotation to the device to thereby effect simultaneous rotation of the endoscopic tube and the electrode means with respect to the handle.

9. A surgical instrument comprising a handle, a device for carrying instrumentalities rotatably and reciprocably mounted upon the handle, an endoscopic tube mounted upon the handle and rotatable with the device, cutting electrode means reciprocable within the endoscopic tube, said electrode means being rotatable and reciprocable with the device, means for imparting rotation to the device to thereby effect simultaneous rotation of the endoscopic tube and the electrode means with respect to the handle, and means carried by the handle to reciprocate the device and the electrode means.

10. A surgical instrument comprising a handle, a device for carrying instrumentalities rotatably mounted upon the handle, a telescope mounted upon the handle and rotatable with the device, cutting electrode means rotatable with the device, and means for imparting rotation to the device for simultaneously effecting rotation of the telescope and the electrode means with respect to the handle.

11. A surgical instrument comprising a handle, a device for carrying instrumentalities rotatably and reciprocably mounted upon the handle, a telescope mounted upon the handle and rotatable with the device, cutting electrode means rotatable and reciprocable with the device, means for imparting rotation to the device for simultaneously effecting rotation of the telescope and the electrode means with respect to the handle, and means carried by the handle to impart reciprocation to the device and the electrode means.

12. A surgical instrument comprising a handle, a device carrying instrumentalities rotatably mounted upon the handle, an endoscopic tube mounted upon the handle and rotatable with the device, a telescope within the endoscopic tube rotatable with the device, cutting electrode means within the endoscopic tube and rotatable with the

device, and means for imparting rotation to the device for simultaneously effecting rotation of the endoscopic tube, the telescope and the electrode means with respect to the handle.

13. A surgical instrument comprising a handle, a device for carrying instrumentalities rotatably and reciprocably mounted upon the handle, an endoscopic tube mounted upon the handle and rotatable with the device, a telescope within the endoscopic tube and rotatable with the device, cutting electrode means reciprocable within the endoscopic tube, said electrode means being rotatable and reciprocable with the device, means for imparting rotation to the device for simultaneously effecting rotation of the endoscopic tube, the telescope and the electrode means with respect to the handle, and means carried by the

5 handle to impart reciprocation to the device and the electrode means with respect to the handle.
